GUN LAYING MECHANISM

Victor Ulrich, Bad Cannstatt, and Richard Diener,
Berlin-Reinickendorf, Germany; vested in the
Alien Property Custodian

Application December 2, 1938, Serial No. 243,640

6 Claims. (Cl. 89—1)

With known gun laying mechanisms which are adjustable to effect different laying speeds, the gun layer, when changing from coarse to fine adjustment, or vice-versa, must interrupt the laying movements. If he uses one hand for the traversing or training gear and the other for the elevating gear, he must remove his hand from one of the laying mechanisms when he wants to change from one laying speed to the other. As a result there occur interruptions in the gun laying operations, and these interruptions, in circumstances when it is necessary to change frequently from coarse to fine adjustment or vice-versa cause undesirable loss of time and hinder the gunner.

According to the invention this discontinuity in the laying operations is avoided by making it possible for the hand controlling a laying movement simultaneously to manipulate the device for changing over from one to another laying speed. This is effected, according to the invention, by combining the handle for changing over from a high to a low speed and vice-versa with the handle for controlling the laying movement in such a manner that the change from one laying speed to the other can be carried out without releasing either of the controls. In this case the member on the laying handle which serves to control the speed of laying is operatively connected with a device for locking the laying mechanism, so that when the handle is gripped the locking device of the laying mechanism is automatically released.

The handle for enabling the speed of laying to be changed from one rate to another may be in the form of a spring pressed lever pivotally mounted in or on the handle. Such a lever has to be held in operative position by the exercise of a certain amount of finger pressure against the spring, so that in course of time the laying operations may become irksome and fatiguing.

This additional hampering effect during the laying operations can be avoided according to a further feature of the invention by designing the control handle as a longitudinally displaceable hand-grip casing which is held positively in one operative position or the other by a locking device, for example a toggle. In this case the hand-grip casing provided with coupling dogs mounted directly thereon, can itself form a coupling member for effecting changes in the laying speeds. It is, however, preferable to utilise the toggle, designed as a snap-action or spring-controlled toggle, which as a result of a longitudinal displacement of the handle moves from a position of rest to one side or the other, to actuate a coupling

member which produces the change in the speed of laying.

One example of construction of a gun-laying machine according to the invention is illustrated in the accompanying drawing in which—

Fig. 1 is a sectional plan view illustrating the invention applied to a traversing or training gear, while

Figs. 2 and 3 are sectional views showing two positions of a modified arrangement.

As shown in Fig. 1, a bearing flange 1 of the gun laying mechanism is securely connected with a part 2 of the upper gun carriage which is pivotally mounted for a swinging movement from side to side while a traversing wheel 3 is securely connected with the lower carriage. With such an arrangement, the gunner invariably remains behind the gun and must follow its traversing movement, but should the converse arrangement be adopted by connection of the bearing flange 1 with the lower carriage and the wheel 3 with the upper carriage, a stationary laying device can be obtained.

The bearing flange 1 carries a locking plate 4 which is provided with recesses 5. The hub of the bearing flange accommodates the hollow hub of a spur-wheel 7 by means of a needle roller bearing 6, which hub houses the bearing pin 8' of a hand-wheel 8. The spur wheel 7 and the hand-wheel 8 are axially fixed relatively to each other and relatively to the hub of the bearing flange 1 by suitable supporting shoulders, intermediate discs, nuts and the like.

To the toothed flange of the spur wheel 7 there is riveted a toothed wheel 9, while on the end of the hub of the wheel 7 which protrudes from the hub of the bearing flange 1 there is keyed a pinion 10 which meshes with the traversing wheel 3.

The hand wheel 8 has a hollow crank pin 11 on which is mounted a hand-grip 12 which is secured against axial displacement by means of a pin 13. In the hollow crank pin 11 of the wheel 8 is a splined wheel hub 16 which is adapted to rotate in the hand-grip 12 by means of a bearing consisting of a bush 14 and rollers 15, the teeth on the wheel of the hub 16 meshing with those on the toothed wheel 9. The hub 16 slidably accommodates and is splined to a wheel axle 17, the teeth on the wheel of which can be brought into mesh either with the teeth 1' of the fixed bearing flange 1 or with the teeth 7' of the spur wheel 7. The axle 17 is biased to the first position by a spring 18 inserted between the axle 17 and the hub 16, the stroke of which is limited by an abutment 17' of the axle 17. By means

of a coupling member or rack 18 which is slideable in the hollow axle 17, this axle can be moved against the pressure of the spring 18', so that the teeth on its wheel mesh with the teeth 7' of the spur wheel 7. For this purpose there is mounted on the handle 12 a lever 19 which is adapted to pivot about a pin 20. A spring 21 thrusts the lever 19 into an angular position relatively to the handle 12, in such a manner that a pinion 23, driven by a toothed segment 22 on the lever 19 when the lever is rocked on the pivot 20. The pinion 23 meshes with teeth on the rear end of the rack 18, and when the lever 19 is in the outer position shown in Fig. 1 the bolt is in its forward or left hand position engaging one of the recesses 5 in the locking plate 4.

With the lever 19 there also co-operates a pawl 25 which is mounted on the handle and is subjected to the influence of a spring 24. This pawl has an abutment 25' which determines a first coupling position of the lever 19 in which the rack 18 is withdrawn from the locking plate 4 and so unlocks the gun laying machine. When the locking bolt is in the first coupling position it has no influence on the axle 17. The teeth on the wheel of the latter thus remain in mesh with the teeth 1' of the bearing flange 1, so that during the laying movement, the wheel of the axle 17 rolls on the bearing flange 1. The hub 16 is thereby moved about the axis of the flange 1 and the teeth on the wheel of the hub 16 therefore rotate the spur wheel 7, with the pinion 10 firmly keyed on its hub of the latter, at a speed which is much lower than that of the crank pin 11, the hub 16, spur wheel 7, and teeth 1' thus forming a transmission of low velocity ratio.

If it is desired to cause the gun to move rapidly through a wide range of laying movement, then, with the palm, or, in the case of a horizontally disposed laying wheel, with, may be, the thumb, of the hand holding the handle 12, the pawl 25 is thrust inwards against the action of its spring 24, until the back 19' of the lever passes behind the projection 25'. Then the lever 19, the spring 21 being further compressed, can be moved deeper into the recess in the handle 12. During this movement, the toothed segment 22 on the lever 19 turns the pinion 23 meshing with it and also the rack 18, through a distance which moves the axle 17 so that the teeth on its wheel move from the teeth 1' of the bearing flange 1 into mesh with the teeth 7' on the spur-wheel 7. The drive to the hub 16 is now direct, the hub 16, teeth 7', and teeth 1' forming a second transmission of higher velocity ratio. Upon returning to fine adjustment, i. e., the slower rate of laying, the handholding the handle relaxes its grip on the lever 19 until the latter swings out over the projection 25' of the pawl 25. In accordance with this movement the rack 18 is thrust forward followed by the axle 17 under the influence of the spring 18'. When the lever 19 has released the projection 25' of the pawl 25, the spring 24 thrusts the pawl back, so that when the lever 19 is again gripped tightly, the fine adjustment is again obtained.

If during the transfer from coarse adjustment to fine adjustment the teeth on the axle 17 do not immediately align with the gaps between the teeth 1', during the next laying movement they will be meshed therein automatically by the spring 18' as will be appreciated.

In the form of construction shown in Figs. 2 and 3, the hand wheel 8, designed as a housing for the laying mechanism, has a guide 8a for

control bar or coupling member 27 which has lugs 27a and 27b forming coupling means with the mechanism in the hand-wheel housing 8 which is provided to adjust for a high or a low laying speed. The bar 27 and lugs 27a, 27b constitute a sliding gear shift member for the two speed gun laying mechanism, not shown, arranged in the housing 8, which mechanism includes any known change speed gear transmission of the type operable by a sliding member, for example a change speed gear transmission of the differential type, different gears of which co-operate respectively with the lugs 27a, 27b of the bar 27 to change the transmission ratio. 15 In a recess 27c in the control bar there engages a nose 28a of a three-armed lever 28 which is pivotally mounted in the interior of the hollow handle 11 and has another nose 28b which protrudes through a slot in the hollow handle 11 into 20 a notch 29, provided between a grip member 29 slidably mounted on the handle 11 and a threaded bush 29a. The end 28c of the lever 28 is jointedly connected with a sliding spring pressed thimble 26 guided in a pivotally mounted bearing 25, 26a and is loaded by a helical spring 26b.

If it is desired to pass from the control position shown in Fig. 2 into that shown in Fig. 3, then, during the laying operation, the grip member 29 is thrust towards the hand-wheel 8 until, 30 after passing the dead-centre position of the toggle joint pin between the lever 28 and the spring box 26, in which position the spring 26b is compressed most strongly, the parts are moved by the spring 26b into the position shown in Fig. 3 35 so that the bar 27 is moved into the other coupling position. When the grip member 29 is thrust outwards, the opposite occurs.

If during change from one laying speed to another the lugs 27a or 27b do not come into engagement immediately with the co-operating members, then, when the spring 26b is tensioned, the parts 26 and 28 remain swung out somewhat beyond the dead centre position until the position of the co-operating members, when the rotation 45 of the hand-wheel is initiated, permits an automatic engagement to occur under the pressure of the spring 26b.

Having now particularly described and ascertained the nature of our said invention and in 50 what manner the same is to be performed, we declare that what we claim is:

1. Gun laying mechanism comprising, means for imparting gun laying motion, a manually movable member for actuating said means, a handle rotatably mounted on said manually movable member in such a manner as to remain stationary within the grasp of the gunner during operation of said member, a first transmission between said means and said manually movable member, a second transmission between said means and said manually movable member, the second transmission having a different velocity ratio as compared with said first transmission, and a manual control device for selectively bringing either of said transmissions into operation, including means for locking the gun laying motion imparting means in a position to which it has been set and means for operatively connecting the manual control device to said means for locking the gun laying motion imparting means.

2. Gun laying mechanism comprising, means for imparting gun laying motion, a manually movable member for actuating said means, a handle rotatably mounted on said manually movable member in such a manner as to remain

stationary within the grasp of the gunner during operation of said member, a first transmission between said means and said manually movable member, a second transmission between said means and said manually movable member, the second transmission having a different velocity ratio as compared with said first transmission, a coupling member in said manually movable member having three operative positions determining respectively operative engagement of said first and second transmissions and locking the gun laying motion imparting means, and a manual control device for selectively bringing said coupling member into any of said positions, said control device being mounted on said handle in a position to be grasped along therewith and operated without change of grip but with increased pressure simultaneously with the operation of said manually movable member.

3. Gun laying mechanism comprising, means for imparting gun laying motion, a manually movable member for actuating said means, a handle rotatably mounted on said manually movable member in such a manner as to remain stationary within the grasp of the gunner during operation of said member, a first transmission between said means and said manually movable member, a second transmission between said means and said manually movable member, the second transmission having a different velocity ratio as compared with said first transmission, a coupling member in said manually movable member having two operative positions determining respectively operative engagement of said first and second transmissions, and a manual control device for selectively bringing said coupling member into either position, including means for locking the gun laying motion imparting means in a position to which it has been set and means for operatively connecting the manual control device to said means for locking the gun laying motion imparting means.

4. Gun laying mechanism, comprising means for imparting gun laying motion, a manually movable member for actuating said means, a handle rotatably mounted on said manually movable member in such a manner as to remain stationary with the grasp of the gunner during operation of said member, a first transmission between said means and said manually movable member, a second transmission between said means and said manually movable member, the second transmission having a different velocity ratio as compared with said first transmission, a coupling member in said manually movable

member having two operative positions determining respectively operative engagement of both said transmissions, and a manual control device for selectively bringing said coupling member into either position including means for locking the gun laying motion imparting means in a position to which it has been set and means for operatively connecting the manual control device to said means for locking the gun laying motion imparting means.

5. Gun laying mechanism, comprising means for imparting gun laying motion, a manually movable member for actuating said means, a handle rotatably mounted on said manually movable member in such a manner as to remain stationary with the grasp of the gunner during operation of said member, a first transmission between said means and said manually movable member, a second transmission between said means and said manually movable member, the second transmission having a different velocity ratio as compared with said first transmission, a coupling member in said manually movable member having two operative positions determining respectively operative engagement of both said transmissions, and a manual control device for selectively bringing said coupling member into either position including means for locking the gun laying motion imparting means in a position to which it has been set and means for operatively connecting the manual control device to said means for locking the gun laying motion imparting means.

6. Gun laying mechanism, comprising means for imparting gun laying motion, a manually movable member for actuating said means, a first transmission between said means and said manually movable member, a second transmission between said means and said manually movable member, the second transmission having a different velocity ratio as compared with said first transmission, a coupling member in said manually movable member having two operative positions determining respectively operative engagement of both said transmissions, and a manual control device for selectively bringing said coupling member into either position including means for locking the gun laying motion imparting means in a position to which it has been set and means for operatively connecting the manual control device to said means for locking the gun laying motion imparting means.
